INVENTOR,

STEPHEN R. MONROE.
BY Franklin Scott, ATTORNEY.

UNITED STATES PATENT OFFICE.

STEPHEN R. MONROE, OF BRISTOL, VERMONT, ASSIGNOR, BY DIRECT AND MESNE ASSIGNMENTS, TO EDWARD C. MARSH, OF SAME PLACE.

ADJUSTABLE HARNESS-LOOP.

SPECIFICATION forming part of Letters Patent No. 546,455, dated September 17, 1895.

Application filed November 6, 1894. Serial No. 528,051. (No model.)

To all whom it may concern:

Be it known that I, STEPHEN R. MONROE, of the village of Bristol, in the county of Addison and State of Vermont, have invented 5 certain Improvements in Adjustable Harness-Loops, of which the subjoined description, in connection with the accompanying drawings, constitutes a specification.

The subject-matter of this patent consists 10 of a small detachable and adjustable spring-wire loop which is capable of application in various situations around an ordinary harness where the otherwise free and unconfined ends of straps, traces, &c., would flap about 15 or curl up and present an unsightly appearance, besides being much in the way. Its structure, application, and mode of use are plainly disclosed in the drawings, in which—

Figure 1 shows a face view of two pieces 20 of an ordinary harness—as, for instance, a portion of a breast-collar and the front end of a tug or trace—with this loop applied. Fig. 2 is an edge view of the same. Fig. 3 is a view of the under strap or part with the loose 25 strap removed so as to show the collapsible character of the loop. Fig. 4 is a face view of the adjustable spring-loop detached from its seat of application. Fig. 5 is a transverse sectional view of two straps or parts taken 30 through the middle of the loop.

It is not uncommon with harness in present use to find the end of a strap protruding a considerable distance beyond the loop which is designed to confine it. This is due sometimes to the strap being taken up to a short bight and sometimes to improper relative proportion of parts. In either case it presents an unsightly appearance for such protruding ends to curl up or hang loosely flap- 35 ping about. The device herein described is provided to take care of such loose ends, and it also constitutes a provision for confining one strap to another, as will be pointed out hereinafter.

40 My invention is made of spring-wire bent in reflecting loops to substantially the form shown in Fig. 4. This spring-loop A may have as many reflections *b b b b* as may be necessary,

and the terminals of the wire are pointed or sharpened down to a thin edge and bent to 50 an acute angle with the length of the strap to which it is to be applied. These sharpened ends, or “tangs,” as they may properly be called, are shown at *c c*, and are intended to pierce the edges of the strap to which they may 55 be applied, as shown at *c c*, Fig. 5. The peculiar configuration of the spring-loop permits distension laterally, so as to accommodate itself to various widths of strap, and after its attachment to a strap, as seen in Fig. 3, the plane 60 of the loops *b b b* can be lifted, so as to pass under them another strap, as in Fig. 2. The tangs may be inserted at any point in the edge of the strap without any special preparation, their shape being such that they may be 65 readily pressed into the leather, or, if necessary, a hole first pierced with an awl to receive them is all that is necessary.

The special advantages of this detachable spring-loop over leather or non-elastic metallic 70 loops are that this may be applied to any position on the under strap, and, by reason of its distensible spring features, it may be applied to straps of various widths without any special adaptation of the loop or previous 75 preparation of the strap to which it is to be attached.

I therefore claim as my invention the following:

An adjustable and detachable spring loop 80 constructed of a single piece of suitable spring wire having its body or central portion consisting of the wire bent back and forth upon itself so as to form reflections or foldings, and having its ends terminating in prongs or tangs 85 which are bent inwardly and transversely of the body reflections, and adapted to be forced into the edges of the strap to which the loop may be attached, substantially as and for the purposes specified.

In witness whereof I have hereto subscribed my name this 28th day of September, 1894.

STEPHEN R. MONROE.

In presence of—

ERSKINE W. SHATTUCK,
WILL WHITTEMORE.
